UNITED STATES PATENT OFFICE.

MAXIMILIAN B. ANFENGER, OF SAN FRANCISCO, CALIFORNIA, ASSIGNOR, BY MESNE ASSIGNMENTS, TO STANDARD OIL COMPANY OF CALIFORNIA, OF SAN FRANCISCO, CALIFORNIA, A CORPORATION OF DELAWARE.

STORAGE SYSTEM FOR AND METHOD OF STORING AND REMOVING FROM STORAGE A LIQUID.

Application filed May 13, 1925. Serial No. 30,076.

This invention relates to storage systems of the type employed, for example, in the storage of petroleum and other oils, and it also relates to methods of storing and removing from storage a liquid, and an object of the invention, in general, is to minimize the fire hazard always present in the storage of oil.

More particularly an object is to provide for the storage of volatile petroleum products or other volatile liquids, in a manner that they will be completely removed from any contact or communication with the atmosphere.

Another object is to reduce the vapor or gas space in the container or tank to a negligible amount.

Another object is to effect the storage of volatile liquids upon a body of water and to effect automatic control of the volume of water in accordance with the volume of the volatile liquids.

Another object is to make it possible to employ a floating roof for the container or tank that is absolutely gas tight.

A still further object is to accomplish the foregoing without it being necessary to make radical departures from a conventional design of the container and without the development of such pressure or partial vacuum in the container as would make it necessary to provide a relatively heavy construction.

The conventional type of storage tank, when partially filled with liquid, contains above the liquid a space filled with a mixture of air and the vapor which rises from the liquid. This mixture is sometimes explosive.

Whenever liquid is introduced into the conventional storage tank, it is necessary to discharge the air and vapor, displaced by the liquid, from said tank. This is undesirable, first, because the vapor is of value and, second, because of the possibility of the inflammable stream of air and gas, that emerges from the tank becoming accidentally ignited, thus setting fire to the entire contents of the tank.

Even when a conventional storage tank for petroleum products is standing idle, the gas above the liquid expands and contracts

as its temperature changes during the day and, consequently, since it is impracticable to construct tanks strong enough to resist the resulting pressure, it is necessary to provide a vent to permit of the discharge of gas when the temperature rises and to permit of the influx of air when the temperature falls. Under such conditions, there is a continual loss of the valuable vapor and there is more likelihood of an explosion taking place than would be the case if the influx of air did not take place.

Attempts have been heretofore made to eliminate the gas or vapor space above the liquid in the storage tanks by two general systems. By the first, a floating roof is used. The floating roof eliminates the gas space by riding up and down on the liquid surface as the tank is filled or emptied or as the level thereof changes because of contraction and expansion of the liquid due to changes of the temperature thereof. In the practical application of such system, however, it is found almost impossible to maintain a vapor tight seal between the floating roof

and the shell of the container and a certain amount of vapor escapes around the edge of the roof. This vapor constitutes a fire hazard and, besides, it is of value. By the second system, the storage tank with permanent roof is kept full of liquid at all times by substituting a volume of water equivalent to the volume of petroleum or other valuable liquid drawn off and by discharging the water as the tank is being filled with the volatile substance. This second system is readily applicable when using small containers, but in the case of relatively large storage reservoirs, it becomes very expensive because of the great strength of construction of the roof, necessary to resist the pressure and partial vacuum that are developed within the reservoir.

As liquids, in so far as they are used in a storage system, are substantially incompressible in such systems, it is necessary in the second system mentioned above, that the change in the volume of water at all times exactly equal the change in the volume of oil or other volatile liquid. The pressure of the water cannot be used to displace the volatile substance, nor can the pressure of

the volatile substance be used to displace the water for, on account of the differences in densities, the roof of the container would be subjected to such pressure that it would have to be made impractically heavy and expensive. Any mechanical synchronizing means installed to control the volume of water would have to function with the greatest delicacy, and the failure of such means to so function, even for a moment, would result in the destruction of the roof of the reservoir.

The present invention aims to avoid the foregoing described difficulties.

13 The accompanying drawings illustrate the invention:

Fig. 1 is a sectional elevation of a storage system embodying the invention, the view being more or less diagrammatic.

20 Fig. 2 is an enlarged sectional fragmental detail to illustrate the liquid seal and the roof drain.

Referring to the drawings, there is provided a storage tank 3, a water reservoir 4, and an elevated stand pipe 5. The stand pipe 5 supplies water through a pipe 6 to the tank 3 and the flow of water to the tank is controlled by a valve 7 on the pipe 6. Water discharges from the tank 3 to a pipe 30 8 into the reservoir 4, there being a valve 9 on the pipe 8 to control the outflow of water from the tank.

Water is fed from the reservoir 4 to the stand pipe 5 through a pipe line 10, there being a pump 11 in said pipe line to lift the water. This pump 11 may be operated by an electric motor 12 to which electric current is supplied through an electric switch 13 that is operated by an arm 14 provided 40 with a float 15 that rests in the body of water in the stand pipe. Dropping of the arm 14 to a lower predetermined level closes the switch so as to pump water from the reservoir into the stand pipe and, when the water 45 in the stand pipe reaches a predetermined higher level, the switch is opened by raising of the arm 14.

The tank 3 has a floating roof 16 which is provided with a flange 17 that dips into a liquid seal 18 surrounding the rim of the tank. Downward movement of the roof 16 is preferably limited by a system of posts 19 inside of the tank. These posts 19 support the roof, in event of the liquid dropping 55 below a predetermined level, as might be caused by failure of the water supply line 6 or drain pipe 8 to properly function. The tank 3 with its floating roof yieldingly confines the liquid *a* that is to be stored and 60 also the liquid *b* that is employed as a seal beneath the liquid *a* to further seal the liquid *a* from the atmosphere.

Upward movement of the roof 16 may be limited by providing an overflow pipe 20 which is connected to the tank at the top

thereof so as to conduct oil away from the tank when said oil rises above a predetermined level.

The roof 16 is provided with a vacuum breaker 21 adapted to function to admit air 70 from the atmosphere to the tank, in the event that the liquid level should fall below the upper end of the posts 19, in order to prevent collapse of the roof. The vacuum breaker 21 can be an inwardly opening check 75 valve.

Water may be carried off from the roof 16 through a drain pipe 22 provided with a flexible section 23 adjacent to the roof so as to be adjustable to the roof as it rises and 80 falls.

It is to be understood that the valves 7, 9 may be manually operated, if desired, but their operation is preferably automatic by reason of the provision of linkages 24, 25 connected with the valves 7, 9, respectively. The linkage 24 is adapted to be operated by the roof 16 to open the valve 7 when said roof falls to a predetermined level and operated to close the valve 7 when said roof rises to a predetermined level, and the linkage 25 is adapted to be operated by the roof to open the valve 9 when said roof falls to a predetermined level and operated to close the valve 9 when said roof rises to a predetermined level. It is understood that any other suitable form of automatic control for the valves, operated by the rise and fall of the roof 16, may be provided in lieu of the linkages described. 100

In the operation of the system described above for performing the new method, when oil is pumped into the tank 3 through the pipe 20, the floating roof rises and upon reaching a predetermined level effects opening of the water drain valve 9 allowing the water to discharge from the tank into the reservoir 4. The drain line 8 and valve 9 are constructed to discharge water at a somewhat faster rate than that at which oil enters the tank. As soon as the drain valve 9 opens, the roof starts to fall, continuing downward to a predetermined level at which the drain valve is closed by operation of the linkage 25. When oil is pumped out of the tank, the roof falls and upon reaching a predetermined level operates the linkage 24, thus effecting opening of the valve 7 so as to admit water from the pipe 6 to the tank. The pipe 6 and valve 7 are constructed to supply water at a somewhat more rapid rate than that at which the oil is removed through the pipe 20, thus causing the roof to rise a distance that can be determined by the adjustment of the linkage 24. When the roof rises to a predetermined level, the linkage 24 closes the valve 7. 115

In event of the level of the liquid *a* falling to the upper ends of the posts 19, owing to improper functioning of the water drain 120

or water supply, the tank will not be injured as the roof will then be supported by the posts. If the liquid *a* should accidentally reach a still lower level so that there would be a tendency to create a partial vacuum beneath the roof, the vacuum breaker 21 admits air to the tank and thus prevents the roof from being collapsed by a partial vacuum.

10 From the foregoing, it will be readily seen that in this system a perfect liquid seal is maintained for the floating roof at all times, and it will be readily understood that it is unnecessary to exactly synchronize the 15 movement of the oil and water, since the rise and fall of the floating roof compensate for any momentary inequalities in the flow of oil and water thus preventing the generation of pressure or partial vacuum within the tank.

20 While the pipe 20 has been described as being used for oil overflow, oil inlet and oil discharge, it is to be understood that separate pipes may be employed for these different purposes, if that be more desirable.

25 I claim:

1. A storage system for liquids comprising a tank having a sealed floating roof, a pipe communicating with the upper portion of the tank, valved water supply means connected with the lower portion of the tank, valved water drain means connected with the lower portion of the tank, means operated by raising of the roof to a predetermined level to open the water drain valve 35 and operated by falling of the roof to a predetermined level to close the water drain valve, and means operated by falling of the roof to a predetermined level to open the water supply valve and operated by raising 40 of the roof to a predetermined level to close the water supply valve.

2. A storage system for liquids comprising a tank having a floating roof, a pipe communicating with the upper portion of the tank, valved water supply means connected

with the lower portion of the tank, means operable by falling of the roof to open the valve and operable by raising of the roof to close the valve, valved water drain means connected with the lower portion of the tank 50 and means operable by raising of the roof to open the drain valve and operable by falling of the roof to close the drain valve.

3. A storage system for liquids comprising a tank having a sealed floating roof, a pipe 55 communicating with the upper portion of the tank, valved water supply means connected with the lower portion of the tank, means operable by falling of the roof to open said valve means and operable by raising 60 of the roof to close said valve means, valved water drain means connected with the lower portion of the tank, and means operable by raising of the roof to open said drain means and operable by falling of the roof to close 65 said drain means.

4. A storage system for liquids comprising a tank having a sealed floating roof, a pipe communicating with the upper portion of the tank, a water standpipe, a valved pipe 70 line connecting the standpipe with the lower portion of the tank, means operable by falling of the roof to open the valve and operable by raising of the roof to close said valve, a reservoir, a valved drain pipe connected with the lower portion of the tank and discharging into the reservoir, means operable by raising of the roof to open the drain valve and operable by falling of the roof to close said drain valve, a pipe line 75 leading from the reservoir to the standpipe, a pump in the last named pipe line, a motor to operate the pump, and means whereby lowering of the water in the standpipe to a predetermined level effects operation of the 80 motor.

Signed at San Francisco, Calif., this 4th day of May 1925.

MAXIMILIAN B. ANFENDER.
